PINTE PORTING

George M. Geiger and Walter Ernst, Mount Gilead, Ohio, assignors to H-P-M Development Corporation, Wilmington, Del., a corporation of Delaware

Application October 27, 1944, Serial No. 560,676

8 Claims. (Cl. 103—161)

1

This invention relates to fluid operable apparatus and, more particularly, to radial pumps and the like.

This invention has for its particular object the provision of a radial pump structure which has improved efficiency and operating characteristics.

Another object of this invention is to provide a porting arrangement for a radial pump which substantially reduces the noise of operation thereof.

These and other objects and advantages will become more apparent upon reference to the accompanying drawings, in which:

Figure 1 is a transverse section through a radial pump having a porting arrangement according to this invention;

Figure 2 is a longitudinal section through the pintle of the pump of Figure 1 and is indicated by the line 2—2 on Figure 1;

Figure 3 is an enlargement of a portion of Figure 1 showing more particularly the pintle and the porting arrangement therein;

Figure 4 is a plan view over a portion of the pintle showing one of the ports therein; and

Figure 5 is a section through a pintle similar to Figure 3 but showing a modified porting arrangement.

Referring to the drawings more in detail, there is shown in Figures 1 and 2 a fluid operable pump comprising a casing 10 having rotatably mounted therein a rotor 12, the latter being supported on antifriction bearings 14 as indicated in Figure 2.

The rotor is radially bored with a plurality of cylinder bores 16 within which are reciprocably mounted a plurality of pistons 18. The pistons 18 comprise an inner portion adapted to be received within the cylinder 16 and an outer portion which comprises a cross head or shoe portion 20 adapted to be received within the slots 22 of the segmented ring 24.

The ring 24 is retained within a member 26 which is guided on a pair of opposed flats 28 within the casing 10. The ring 24 is rotatable within the member 26 and, to that end, is mounted on suitable antifriction bearings, not shown.

The rotor 12 is centrally axially bored at 30 to receive a pintle or valve member 32. The member 32 is mounted within the casing in any suitable manner and the aforementioned antifriction bearings 14 are mounted thereon. The valve member 32 is provided with a pair of longitudinal bores 34 which are in communication with the port 36 in the casing and terminate, at their inner ends at the port 38 of the valve member 32. The port 38 is adapted to communicate with the

2

cylinder bores 16 through the apertures 40 in the lower ends thereof.

The pintle or valve member 32 is likewise provided with a pair of bores 42 which communicate the port 44 in the casing 10 with the port 46 of the member 32. The ports 46 and 38 are preferably arranged diametrically opposite on the member 32.

Suitable control means such as the rods 48 and 50 may be provided which extend through apertures in the casing and engage the member 26. By this means, the member 26 may be moved in response to any predetermined stimuli in order to vary the eccentricity of the ring 24 relative to the rotor 12 and valve member 32. In a manner well known in the art, the shifting of the ring 24 to vary its eccentricity is effective to vary the rate of discharge of the pump.

Assuming that the rotor in Figure 1 rotates in a counter-clockwise direction, the cylinders in communication with the lower port 38 are withdrawing fluid therefrom while the cylinder bores in communication with the upper port 46 are expelling fluid therein. Thus, fluid is continuously drawn in through the port 38 and expelled, at increased pressure, through the port 46.

It has been found that pump units of the type disclosed in Figures 1 and 2 operate with considerable noise whenever the pump is under load, or is discharging fluid, even if the said load is light. Numerous experiments have been conducted in order to ascertain the exact cause of these noises in order, if possible, to eliminate them. It has been found that, in the usual type radial pump having a space between the suction and discharge ports greater than the diameter of the bores 40, considerable noise is caused by the fact that the cylinder cavity is not completely filled before the same is sealed off from the suction port. When the cylinder chamber is sealed off from the suction port before the piston has completed its outward movement, a vacuum is drawn within the cylinder which, upon being relieved as the cylinder moves toward the discharge port, creates an objectionable noise.

This phenomenon is known as cavitation and it has been established that it is the principal source of noise in a radial pump when the same is discharging under low pressures.

It will also be apparent that a certain volumetric loss will take place when the phenomenon of cavitation occurs. Accordingly, an arrangement which would eliminate cavitation would tend not only to reduce the generated noises but would

also increase the volumetric efficiency of the pumping unit.

We have found, by experiment and test, that a porting arrangement substantially as shown in Figure 3 is effective largely to eliminate cavitation and the noises therefrom in a radial pump. In this figure a suction port 38 is so arranged that the port 40A of the cylinder which is at the point of being sealed off from the suction port is beyond the center line B before the said sealing off is accomplished. This is effected by cutting back the right hand edge of the suction port so that there is substantial communication between the suction port and the cylinder until after the piston associated with the said cylinder has commenced its inward movement. It will be apparent that, while the communication between the suction port and the cylinder is gradually cut off due to the arcuate end shape of the said port, the area through which fluid may pass into the cylinder is great enough to prevent cavitation. The extent of the communication between the port 38 and the port 40A, when the latter is aligned with the center line B, is indicated by the dimension C.

The discharge port 46, on the opposite side of the valve member 32, is of a standard design and may be so arranged that the portion 52 of the valve member between the suction and discharge ports is of substantially the same length as the diameter of the ports 40 at the cylinders 16. We have found, however, that the length of the space 52 may be somewhat less than the diameter of the port 40 without materially affecting the capacity or efficiency of the pumping unit.

The utility of the porting arrangement shown in Figure 3 is further increased if the leading, or left hand edge of the port 38 is formed so as to be symmetrical with the right hand edge thereof. With the port so shaped it is possible to drive the rotor 12 in either direction by shifting the ring 24 so as to lay on the opposite side of the center line.

A somewhat modified porting arrangement is shown in Figure 5 wherein the suction port 38b and the discharge port 46b of the valve member 32b are similarly shaped and symmetrically located with respect to the horizontal and vertical center lines of the valve member. In Figure 5 the lap portion 52b is substantially equal to the diameter of the apertures 40b in the lower ends of the cylinders.

In the arrangement of Figure 5 the cylinders are in communication with the suction port until they are coaxial with the horizontal center line of the valve member. Thus, cavitation and the noise caused thereby is substantially eliminated. It will be apparent that, while the arrangement of Figure 3 is such that the port 38 must always be on the suction side of the pump, the arrangement of Figure 5 permits either the port 38b or the port 46b to act as the suction port. Thus, while the arrangement of Figure 3 permits the ring 24 to be shifted to only one side of center for a given direction of rotation of the rotor, the shift ring associated with the arrangement of Figure 5 is shiftable across center so that the delivery of the pump may be reversed at will.

Accordingly, we prefer the arrangement shown in Figure 3 for a one-way delivery pump and the arrangement shown in Figure 5 for a two-way delivery or reversible pump.

As an example of the improvement in the operating characteristics of a pump provided with the improved design of suction ports, a

pump having standard ports according to the prior art was found to operate at a noise level of approximately 96 decibels, while the same pump with a valve member having a suction port formed according to this invention was found to operate at a noise level of only 77 decibels. These readings were recorded with the pumps discharging at their maximum rate and under relatively low pressures.

At the same time, a somewhat increased rate of discharge was noted, indicating that the improved porting arrangement had eliminated cavitation and provided an arrangement somewhat more efficient volumetrically as well as quieter in operation.

It will be apparent that the particular arrangement set forth in the drawings is not necessarily the only possible means by which the objects of this invention may be accomplished. For example, we have found that certain improved results are obtained in a pump having a standard valve member if the latter is rotated in the direction of rotation of the rotor so that the communication between the suction port and the cylinders is not cut off prior to the said cylinders passing the horizontal center line of the pump unit. Likewise, so long as the porting arrangement is not varied, and should it be necessary in order to increase the strength of the valve member, the particular shape of the solid web portion of the valve member may be varied without in any way departing from the scope of this invention.

Accordingly, we desire to comprehend such modifications in structure and arrangement and substitution of equivalents as may be considered to come within the scope of the appended claims.

We claim:

1. In a fluid operable pump having a valve member and variable capacity pumping means adapted for transferring fluid from an inlet to an outlet in said valve member, the improvement comprising forming said inlet so that communication is had between said inlet and said pumping means until the latter has attained its maximum capacity and has commenced discharging.

2. In a fluid operable pump having a valve member with an inlet and an outlet and pumping means adapted to vary in volume between predetermined limits in order to transfer fluid from said inlet to said outlet, the improvement comprising forming said inlet port so that the pumping means has attained its maximum volume a predetermined minimum time before the fluid communication between said pumping means and said inlet port is interrupted.

3. In a fluid operable pump having an inlet port and an outlet port and piston-cylinder means for transferring fluid between said ports, the improvement comprising arranging said inlet port to communicate with said cylinder means until after said piston means has commenced its discharge stroke.

4. In a fluid pump, an inlet port and an outlet port, cylinder means adapted to communicate with said ports, piston means reciprocable in said cylinder means for drawing fluid therein from said inlet port and for discharging fluid therefrom into said outlet port, the said inlet port being adapted to communicate with said cylinder means at least until said piston means has commenced its discharging movement.

5. In a fluid pump, a valve member having a spaced inlet and outlet, cylinder means having

port means adapted to communicate with said inlet and said outlet, piston means movable in said cylinder means for drawing fluid therein from said inlet and for discharging fluid therefrom into said outlet, said inlet and said outlet being spaced apart a distance no greater than the diameter of said port means and said inlet being so located as to communicate with said port means until said piston has commenced its discharging movement.

6. In a fluid pump, a plurality of substantially radially extending cylinders, a plurality of pistons reciprocable in said cylinders, a valve member centrally located relative to said cylinders and having an inlet and an outlet, port means in said cylinders adapted to communicate successively with said inlet and said outlet, means adapted to be eccentrically positioned relative to said valve member and to engage said pistons for actuating the latter in response to rotation of said cylinders and pistons relative to said valve member, said inlet and said outlet being spaced on said valve member by a distance not greater than the diameter of said port means, and said inlet being of substantially greater circumferential length than said outlet to maintain communication with said port means until said pistons commence their inward movement.

7. In a fluid pump, a rotor, a plurality of substantially radial cylinders in said rotor, a plurality of pistons reciprocable in said cylinders, a central bore in said rotor connected with said cylinders, a valve member extending into said bore, a piston actuating member in engagement with the outer ends of said pistons and adapted to be eccentrically located relative to said valve member so that rotation of said rotor is effective to cause said member first to move said piston outwardly and then inwardly in said cylinders, said valve member comprising an inlet port having arcuate ends adapted to communicate with said cylinders throughout said outward movement of said pistons and during a portion of their inward movement, and an outlet port spaced from

said inlet port by a distance substantially equal to the diameter of the openings in said cylinders.

8. In a fluid pump, a rotor, a plurality of cylinder means substantially radial and coplanar in said rotor, piston means reciprocable in said cylinder means, a central bore in said rotor, a stationary valve member adapted closely to be received in said bore, port means in said cylinders communicating with said bore and therefore with the surface of said valve member, means for actuating said pistons comprising a member in engagement with the ends thereof, said member being adapted to be horizontally moved into a position eccentric to said valve member, and means for actuating said rotor so as to cause said pistons to be reciprocated by said member, said valve member comprising an inlet and an outlet each arranged in the plane of said cylinders and symmetrically about the vertical center line of said valve member, said inlet port being adapted to communicate with said port means from prior to the beginning of the outward movement of said piston means until after the beginning of the inward movement thereof, and said outlet having the ends thereof spaced from the ends of said inlet a distance substantially equal to or slightly less than the diameter of said port means.
